UNITED STATES PATENT OFFICE.

EDWARD WILLIAM MACKENZIE HUGHES, OF CHICAGO, ILLINOIS, ASSIGNOR
TO THE FOX SOLID PRESSED STEEL COMPANY, OF SAME PLACE.

CENTER PLATE FOR RAILWAY-CARS.

SPECIFICATION forming part of Letters Patent No. 408,032, dated July 30, 1889.

Application filed May 23, 1889. Serial No. 311,878. (No model.)

To all whom it may concern:

Be it known that I, EDWARD WILLIAM MACKENZIE HUGHES, of Chicago, Cook county, Illinois, have invented a new and useful Improvement 5 in Center Plates, of which the following is a full, true, and exact description, reference being had to the accompanying drawing.

This invention relates to an improvement in center plates especially as applicable to trucks; 10 and it consists in making said center plates of pressed steel fitting each other in part, but at the same time so shaped as to allow a rolling or rocking motion of one plate over the other.

15 My invention will be readily understood from the accompanying drawing, which is a vertical section through my two plates A B.

The plate A consists, essentially, of the spherical-shaped portion C and an inside cylindrical portion D. The plate B consists, essentially, of the spherical-shaped portion E, fitting the surface C, and the inner cylindrical part F, located within the exterior cylindrical part D. Between the parts F and D 25 a space G is left, as indicated. These center plates are made of pressed steel pressed between dies, so as to make them exactly fit one upon the other and secure perfect continuity

of bearing-surface between E and C, while, on the other hand, the parts D and F being 30 separated from each other by the space G, the parts E and C may roll upon each other within the limits of that space, as can be clearly seen from the drawing. The spherical surfaces allow a rolling motion in any direction, like a universal joint. Of course their surfaces do not require to be exactly spherical, but should be so shaped as to allow the sliding of one over the other. 35

What I claim as my invention, and desire to 40 secure by Letters Patent, is—

The combination of the pressed-steel center plates A and B, having contact wearing-surfaces E C and cylindrical portions F D, the said cylindrical portions being separated 45 by the space G, so as to allow the rocking of the plate A upon the plate B in any direction, substantially as described.

In testimony whereof I have signed my name to this specification in the presence of two 50 subscribing witnesses.

EDWARD WILLIAM MACKENZIE HUGHES.
